(No Model.)

G. H. REYNOLDS.
ELEVATOR.

No. 313,241.

Patented Mar. 3, 1885.

UNITED STATES PATENT OFFICE.

GEORGE H. REYNOLDS, OF NEW YORK, N. Y., ASSIGNOR OF ONE-HALF TO
CRANE BROTHERS MANUFACTURING COMPANY, OF CHICAGO, ILL.

ELEVATOR.

SPECIFICATION forming part of Letters Patent No. 313,241, dated March 3, 1885.

Application filed November 28, 1884. (No model.)

To all whom it may concern:

Be it known that I, GEORGE H. REYNOLDS, of the city and county of New York, in the State of New York, have invented a new and 5 useful Improvement in Elevators, of which the following is a specification.

My invention relates to both freight and passenger elevators which are operated either by steam, hydraulic, or other power. The 10 car, cab, or platform of a modern elevator is usually provided, in addition to the hoisting ropes or cables, with a counterbalance rope or cable, to which is attached a weight nearly equal to the weight of the car, cab, or platform without any load. As now arranged, the hoisting-cables and counterbalance-cables are entirely 15 distinct from each other, and in case of the parting of the hoisting-cables the car or cab would, in case of the failure of the safety appliances to act, fall with a force proportioned to the unbalanced weight therein, while the counterbalance-weight would crash upward to the top of the shaft, and in case of the 20 counterbalance-cables parting by the shock would fall to the bottom of the shaft. In case of the parting of the counterbalance-cables, the hoisting-cables remaining intact, the weight will fall at once to the bottom of the shaft.

An important object of my invention is to 25 supersede this entire separation of the hoisting and counterbalance cables by an arrangement whereby, in case of the parting of the counterbalance-cables, the counterbalance-weight will be automatically and instantly 30 transferred to the hoisting-cables, and in case 35 of the parting of the hoisting-cables the weight of the car or cab will be sustained by the counterbalance-cables; and raising and lowering of the car will be performed with the aid 40 of the counterbalance-cables.

In the accompanying drawings, Figure 1 is 45 a perspective elevation of an elevator-cab with its hoisting and counterbalance cables and counterbalance-weight arranged and combined according to my invention. Fig. 2 is an elevation of portions of the cables and the weight on a larger scale. Fig. 3 is a plan of the weight and a horizontal section of the cables;

and Fig. 4 is a plan of a clamp which is secured to the hoisting-cable immediately over 50 the counterbalance-weight, and which is shown in Fig. 2.

Similar letters of reference designate corresponding parts in all the figures.

A designates the car, which is to be raised 55 along guides in a shaft not here represented. It is now customary to employ a number of hoisting-cables, and I have here shown four hoisting-cables, B, which are attached to the cab by suitable connections, such as are ordinarily used, and which are carried or passed over the usual sheaves, C, which may be one or more in number, and from thence downward to the motor which produces the rising and falling movement of the cab, whether 60 such motor be a steam elevator engine, a shaft driven by power, or a hydraulic cylinder and piston. I have not shown any motor, as it forms no part of my invention.

D designates the counterbalance-weight, 70 which is suspended by cables E, which are here shown as two, formed by a single wire rope of proper size, having its bight E' secured fast in the weight, and thereby forming the equivalent of two separate ropes. As 75 here shown, the counterbalance-cables E are carried over the same sheaves, C, which carry the hoisting-ropes B.

It is not essential to my invention that the two sets of cables B E should be carried over 80 the same sheaves C; but it is very important that the downwardly-extending portions of the hoisting ropes or cables B should be closely adjacent to the weight D. In this example of my invention the weight D is slotted or 85 open at the center, a, and through the opening thus provided the cables B depend freely and without binding in the weight. The said weight is composed of two parts, as here shown, or is divided vertically, and said two 90 parts are held together by bolts b and nuts or other suitable means. The bight E' of the counterbalance-cables E rests in a groove between the two sections, and is thereby securely held between them and attached to the weight. 95 During ordinary operation, and so long as

both the cables D and E remain intact, the weight and cables move together, and as the hoisting-cables B are kept taut by the weight of the car or cab upon them, they serve in a 5 measure to guide the weight, and no slideway or other guide therefor will be necessary unless the space for the movement of the weight is much restricted, in which event ordinary fixed guides may be provided for the weight. 10 During ordinary operation the weight is wholly sustained by the counterbalance-cables E, and no part of such weight comes upon the hoisting-cables.

Upon the hoisting ropes or cables B, immediately below the weight D, is secured a clamp, F, and secured to said ropes or cables above the weights is a similar clamp, F'. Each of these clamps may consist of two parts or sections, notched or grooved on their adjacent 15 faces for the cables B, and clamped securely thereon by bolts d. The upper clamp, F', extends beyond the counterbalance-cables E in this example of the invention, but does not bite thereon, the recesses e in the clamp-sections being so large that they do not hold on the cables E, as is most clearly shown in Fig. 4.

The clamps F F' form stops or abutments on the hoisting-cables, and may be of any suitable construction, the only requisite being that they 20 shall be capable of being secured on the hoisting-cables so tightly as to render their accidental displacement impossible. They are arranged in such relation to the weight D that when the weight hangs solely suspended by its cables E 25 the clamps, stops, or abutments F F' will be just out of contact with the ends of the weight. Suppose, now, that the counterbalance-cables E part. The weight, instead of crashing down the shaft, settles slightly and rests and is supported on the lower clamp, stop, or abutment, F, and is thereby simply transferred to the hoisting-cables B. It still serves its purpose as a counter-balance, and the running of the elevator with the weight on the hoisting-cables 30 may be continued until a new counterbalance-cable can be procured. On the other hand, suppose that the hoisting-cables B part between the weight and the car or cab. The car or cab, being entirely free from the hoisting-cables, settles slightly, thereby raising the 35 weight until it comes against the upper stop, clamp, or abutment, F', whereupon the car or cab is arrested, and the counterbalance-cables E are transformed into hoisting-cables, and 40 may continue to serve such purpose until new hoisting-cables can be procured; hence the car cannot fall in the event of the hoisting-cables parting and the safety appliances failing to act.

I have referred herein to safety appliances in a general way as they are now universally used on elevators. Any suitable appliances may be used, and they form no part of my invention.

It is not essential that the hoisting-cables B 45 should pass through the weight D; but they should be so closely adjacent thereto that the clamps F F', which form the stops or abutments, are within the range or path of the weight in its rise and fall.

What I claim as my invention, and desire to secure by Letters Patent, is—

1. The combination, with an elevator car, cab, or platform and its hoisting and counterbalance cables, of a weight suspended by the 50 counterbalance-cable and a stop or abutment upon the hoisting-cable below the weight and in the path thereof, whereby the weight will be sustained by said stop or abutment and hoisting-cable in case the counterbalance-cable parts, substantially as and for the purpose herein described.

2. The combination, with an elevator car, cab, or platform and its hoisting and counterbalance cables, of a weight suspended by the 55 counterbalance-cable and a stop or abutment on the hoisting-cable above the weight and in the path thereof, whereby the counterbalance-cable will be transformed into a hoisting-cable in the event of the hoisting-cable proper 60 parting, substantially as and for the purpose herein described.

3. The combination, with an elevator car, cab, or platform and its counterbalance cable and weight, of a hoisting cable or cables 65 received through said weight, and provided below the weight with a stop or abutment to sustain the weight on the parting of the counterbalance-cable, substantially as herein described.

4. The combination, with an elevator car, cab, or platform and its counterbalance cable and weight, of a hoisting cable or cables received through the said weight, and provided above the weight with a stop or abutment which will arrest the rising movement 70 of the weight if the hoisting cable or cables part, substantially as and for the purpose herein described.

5. The combination, with the car, cab, or platform, of the hoisting and counterbalance cables, a hollow weight suspended by the counterbalance-cable and receiving the hoisting-cable through it, and stops or abutments on the hoisting-cable above and below said 75 weight, substantially as and for the purpose herein described.

6. The combination, with the car, cab, or platform, of a counterbalance cable or cables consisting of a single cable doubled upon itself and having its ends secured to the car, cab, or platform, and a counterbalance-weight suspended from the bight of the double cable, substantially as herein described.

7. The combination, with the car, cab, or platform and its hoisting and counterbalance cables, of a hollow weight to which the counterbalance-cable is attached and through which

the hoisting-cable depends, whereby the weight is guided by the hoisting-cable, substantially as herein described.

8. The combination, with the car, cab, or platform and its hoisting and counterbalance cables, of sheaves common to both cables, and a hollow weight to which the counterbalance-

cable is attached and through which the hoisting-cable depends, substantially as herein described.

GEO. H. REYNOLDS.
